(57) **CLAIM**

The ornamental design for a hair bow carrying case, as shown and described.

DESCRIPTION

FIG. 1 is a perspective view of the hair bow carrying case in full lines.

FIG. 2 is an alternate perspective view of the hair bow carrying case shown open in full lines, with a hair bow inside the carrying case shown in broken lines representing environmental association matter being for illustrative purposes only and forming no part of the claimed invention.

FIG. 3 is a front elevational view of the hair bow carrying case.

FIG. 4 is a rear elevational view thereof.

FIG. 5 is a top plan view thereof.

FIG. 6 is a bottom plan view thereof.

FIG. 7 is a right side elevational view thereof; and,

FIG. 8 is a left side elevational view thereof.
